APPARATUS FOR SUPPLYING REINFORCEMENTS FOR ATTACHMENT

Lester S. Macdonald, Beverly, Mass., assignor to
 United Shoe Machinery Corporation, Borough
 of Flemington, N. J., a corporation of New
 Jersey

Application May 11, 1939, Serial No. 273,049

21 Claims. (Cl. 1—32)

This invention relates to apparatus by which reinforcing means may be supplied to a machine by which they are to be attached. Especially, the invention is concerned with the delivery to heel-attaching machines of the plates which are applied to the thread-surfaces of heels to protect them against wear.

It is a common practice to reinforce the thread-surfaces of shoes by generally horseshoe-shaped metal plates attached by nails, driven through openings in the plates and through lifts or whole heels to secure these in place upon the heels or the heel-seats of shoes. An object of my invention is to supply such reinforcements of varying sizes accurately, as to their positions with respect to the heel-portion to which they are to be nailed, and in a manner which will minimize effort on the part of the operator.

To attain this object, I combine with a heel-holder, as the customary heel-ring movable into and out of co-operation with nailing mechanism, means for supplying reinforcements to said holder, through which reinforcements nails are driven by the nailing mechanism into heels contained in the holder. The reinforcement may thus be positioned in the holder when this is separated from the nailing mechanism, and said holder is then returned to receive a heel for attachment simultaneously with the reinforcement. Preferably, the reinforcements are contained in one or more magazines from which they are ejected successively into the holder. To reduce the burden upon the operator, the delivery of the reinforcements is made dependent upon another act which he must perform, as the transfer of nails to the nailing mechanism. There is herein disclosed a movable heel-ring and an ejector movable into a magazine-tube, there being connections to a mechanism, as that for loading nails into the die-block of the heel-attaching machine, for controlling the movement of both the heel-ring and the ejector. The movement of the ejector is best effected by a spring, which is tensioned as the ring is carried into its receiving position, and then permitted to act under the control of a cam actuated from the loading mechanism. To enable the operator to choose conveniently any one of a number of sizes of reinforcements for attachment, as the work in hand may demand, a plurality of magazines may be provided, which may be brought selectively into delivering relation to the heel-holder. In the illustrated embodiment of the invention, these magazines are mounted upon a rotatable turret. A chosen magazine may be located in

its delivering position with respect to the holder, by means which it carries and which may consist of a roll supporting it as the turret rotates and which, by movement of the magazine upon the turret, enters a depression in the surface upon which it travels to produce the locating effect. Means, movable by the operator, may be utilized to free the turret from the locating means, as by the elevation of a magazine to remove its roll from the depression. By means variable in position in each magazine, this may be adapted for holding reinforcements of different sizes. This means is herein shown as a post rising through the magazine and a side wall, both the post and wall being adjustable. To guard against the ejected reinforcement being thrown beyond the opening in the holder which it is to enter, means in the form of a wall is provided which will deflect the reinforcement into the holder. This wall is preferably adjustable to cause it to act effectively upon the various sizes of reinforcements.

One of the many forms which my invention may assume is illustrated in the accompanying drawings, in which:

Fig. 1 is a broken front elevation of the apparatus mounted upon a heel-attaching machine;

Fig. 2, a top plan view of the apparatus and more closely associated portions of the heel-attaching machine; and

Fig. 3, an enlarged vertical section on the line III—III of Fig. 2.

At 10 appears a portion of the frame of a heel-attaching machine, such, for example, as is disclosed in Letters Patent of the United States No. 351,157,688, Glidden, October 26, 1915, this being adapted for the attachment of a heel to a shoe by the insertion of nails through the tread-end of said heel and the heel-seat of the shoe, where they are clinched upon the insole. The shoe is presented upon a jack 12 to be pressed against a heel supported over a die-block 14. Through passages in this die nail-drivers 16 reciprocate. The present invention is preferably combined with a heel-holder, such as that of Letters Patent of the United States No. 1,365,802, Standish, January 18, 1921, which has a ring or plate 18 mounted in a frame 20 and with an opening 22 formed to receive a heel, and, in the present instance, a reinforcing plate, with its tread-surface down and positioned over the die-block for nailing. The reinforcing plates are shown at P in Fig. 2, each being of metal of generally horseshoe-shape and provided with openings p, through which the attaching nails are to be

driven. The frame 20 is arranged to slide at 24, 24 upon the support 25 of the die-block, so it may be shifted back and forth between the active or nailing position of Figs. 1 and 2, and one at 5 the left, where it receives the reinforcing plate, as appears in Fig. 3. This reciprocation may be effected by the link 26 joining the frame to a loader-arm 28, which oscillates between the foot-plate of a nail-distributor (not illustrated) and 10 the die, to respectively receive nails in its block 29 and deliver them for the attachment of the heel-portions. Interchangeable rings 18 are provided, one for each of the various sizes of reinforcements. These rings are so arranged in the 15 frame 20 that the rear extremities of all sizes of the reinforcements and their rear openings are respectively at the same points in their receiving and nailing positions.

Considering the features peculiar to the present invention and especially the means for supplying reinforcing plates to the ring 18, there is secured to the left of the machine-frame 10, at about the level of the die-block 14, a bracket 30. Rising from the bracket is a vertical spindle 32, 25 surrounded at the bottom by a bearing or spacing ring 34. Upon this ring rests the rotatable spider 36 of a turret T. At the periphery of this spider is a series of vertical ways 38, shown as six in number, equally spaced from one another 30 circumferentially (Fig. 2) and each divided into two vertically separated sections (Fig. 1). These ways receive correspondingly separated 35 projections 40 from a bar 41, to which is attached at 42 the inner side of a vertically extending magazine-tube 44, the horizontal contour of which may approximate that of the peripheries of the reinforcements which they are to contain. Each tube is partially closed at the bottom by a plate 46, upon which rests a 40 stack of the reinforcements, upwardly extending lugs 48, at the ends of each of the spaced arms, being secured to the tube and having a cross-bar 50 connecting them. At the front of the plate 46 is an opening through which the bottom 45 reinforcement of the stack may fall when it is pushed forward.

It is preferable to arrange each magazine-tube to hold a plurality of sizes of reinforcements. To permit this, and considering one only of the tubes, there rises from the bottom a post or locating member L. This may be formed of a strip of sheet-metal, having at its lower extremity parallel arms 52 and 54, respectively below and above the bar 50. From the lower arm, an upright 56 extends substantially to the top of the tube in a direction parallel to the rear curved wall. The member is then bent downwardly and outwardly at 58, terminating in the arm 54. This arm is slotted longitudinally and through the slot 60 passes a screw 60 threaded into the arm 52. The screw clamps the post to the bar, allowing the former to be adjusted so the upright 56, for engagement with the inside of the stack of reinforcements P, will hold said reinforcements with 65 their opposite or outer edges in close proximity to the wall of the tube. This places these edges all in the same vertical line, and the mounting of the tubes upon their projections 40 is such, that the rear walls of all the tubes are at the 70 same distance from the radii of the spider which pass through the centers of the projections. This prepares for the ejection of the reinforcements from all the magazines into opening 22 of the plate 18 for any size of reinforcement, when this 75 is in receiving position, by a delivery member

movable through an unvarying distance. To locate symmetrically reinforcements varying in width laterally of the tubes, there is in the lower portion of each of said tubes and at each side thereof, an adjustable inner wall 62 of sheet- 5 metal. This may occupy positions close to the tube-wall for the wider reinforcements, or may be caused to converge inwardly and downwardly to centralize narrow reinforcements. At their tops, the walls 62 are secured pivotally by screws 10 64 passing through their out-turned flanges 66 and flanges 68 of the tubes. At the bottom, the wall-flanges are widened and provided with arcuate slots 70, through which are screws 72 threaded into the tube-flanges. The walls may, 15 therefore, be bent in and out and secured by the screws 72. The effect of the positioning means upon the reinforcements will be understood upon the comparison of the different magazine-tubes in Fig. 2. 20

Any one of the tubes 44 may be brought selectively into delivering position by rotation of the turret T by the operator. That tube at the extreme right of the turret in Fig. 2 is so situated. In the rotation of the turret, each tube is supported as it travels by a roll 76, rotatable about a horizontal axis at the bottom of the corresponding bar 41 and bearing upon a horizontal surface 78 of the bracket 30. When the magazine-tube which the operator has chosen reaches the delivering position, the roll and the adjacent end of its bar enter a depression 80 formed in the surface 78, the projections 40 sliding in the ways 38. The turret is thereby held against rotation. To further and more exactly locate the selected tube by means carried directly upon it, its plate 46 has depending from it a projection 82, which, as the tube falls, is received by an opening 84 in the horizontal surface of the bracket 30. To free the positioned tube, so that the turret may be 40 turned to present another for delivery, there is arranged to reciprocate vertically in the bracket 30 a slide 86, having an arm 88 extending beneath the roll. Pivoted below the bracket is a hand-lever 90, the inner end of which engages the 45 lower extremity of the slide. Upon actuation of the lever, the slide, roll, bar and tube are raised, with said roll above the surface 78. Thereupon, the operator may turn the turret to its new position, the roll travelling from the upper surface of 50 the arm 88 on to and over the bracket-surface. In this elevation of the tube, it is brought to such a level that the lower portion will travel clear of the ways 94 of a reinforcement-delivering slide 96, arranged to reciprocate horizontally upon the 55 bracket 30. 30

When the nail-delivering movement of the loader-arm 28 effects the advance of the heel-ring 18 to its reinforcement-receiving position, it also causes the slide 96 to eject a reinforcement P 60 from the magazine-tube 44 which is in delivering position. In this feeding action, the forward extremity of the slide enters openings 98, 98 in the vertical wall of the tube just above the bottom-plate 46, there being a division at 100 in the slide 65 to permit it to pass the post L. A link 102, adjustably connected to the slide 96 in a slot 104, is joined to an arm 106 pivoted at 108 upon the bracket 30. A torsion-spring 110, surrounding the arm-pivot, urges a roll 112 rotatable upon the 70 arm against a cam-surface 114 upon a lever 116, fulcrumed at 118 adjacent to the pivot 108. A link 120 unites the cam-lever to the loader-arm. As said loader-arm carries in the openings of its block 29 a load of nails to the die 14, the link 26 75

advances the frame 20 of the ring 18 so that, when the load of nails is deposited in the die-passages, the ring-opening 22 is beneath the selected magazine-tube. During the travel of the 5 ring, a portion *a* of the cam-surface 114, concentric with the axis of its fulcrum 118, is moving along the roll 112, so the arm 106 and the slide 96 remain stationary. But when the ring is ready for the reception of its reinforcement, the roll 10 is freed by a portion of the cam-surface at *b* having an abruptly decreasing radius. The spring 110 now acts to urge the slide through the openings 98 into the magazine-tube, where it engages the reinforcement at the bottom of the stack and 15 forces this forward beneath the arm 52 of the post L to descend through the opening in the plate 46 into the opening 22 of the ring. To prevent the ejecting force from throwing the reinforcement beyond the ring-opening, a stop or deflecting member is located in the path of said reinforcement above the forward edge of the opening. It may consist of a wall 122 (Fig. 3), inclined downwardly and outwardly beneath the arm 52 of the post L, and then bent outwardly, 20 upwardly and inwardly where it is adjustably secured by slot-and-screw connections 124 (Fig. 2) to the bar 50 of the magazine-tube. Its position, toward and from the delivery-opening from the tube at the front of the plate 46, may be 25 varied to cause it to act most effectively for reinforcements of different dimensions and weights. Upon entering the ring-opening 22, the reinforcement rests upon a horizontal plate 126, which is secured to the die-block-support 25. The upper 30 surface of this plate is flush with the upper face of the die-block. When the loader-arm is swung back to receive the succeeding load of nails in the block 29, the ring 18 will be restored to its normal relation over the die-block. In its travel, the reinforcement contained in the ring-opening slides over the plate 126 and the die-block and comes 35 to rest in its attaching position, with its openings *p* in registration with the driver-passages of the die-block.

40 In using my improved supplying apparatus, the operator places in the frame 20 a ring 18 having an opening 22, of such contour that there will fit within its lower portion the reinforcement P to be attached, while in the upper portion will fit a heel or heel-lift to which the attachment is to be made. The two heel elements will be in a definite transverse relation to each other, so if the upper 45 is a rubber lift in which are washers, the openings of said washers will register with the openings *p* of the reinforcement. The magazine-tubes 44 of the turret T may contain all the sizes of reinforcements which the operator will be called upon to use during his day's work. Each tube will have its post L and walls 62 adjusted to hold the 50 stack in proper position. The nailing design of the die-block 14 and of the loader-block 29 will, of course, also correspond to that of the openings *p*. If the desired size of reinforcement is not contained in the magazine which is located in 55 delivering position by its roll 76 and projection 82, the operator will depress the lever 90 to free the magazine and will then rotate the turret, the rolls of all the magazines travelling over the bracket-surface 78. The slide-arm 88, which effects the release of the magazine, will be kept raised until the one chosen arrives in position, whereupon it is released and the roll and projection of such magazine will descend and lock it 60 positively in the correct relation. The arm 28, with a load of nails in its block 29, may now be

turned clockwise (Fig. 2) until the load is deposited in the die-block-passages. During this movement of the arm, the link 26 carries the heel-ring 18 from above the die-block to beneath the positioned magazine-tube and there temporarily holds it. As the link 26 acts, the link 120 is oscillating the lever 116, so its concentric cam-surface *a* moves along the roll 112, holding the ejecting slide 96 against movement by its tensioned spring 110. But when the surface *b* of the 10 cam reaches the roll, as the ring 18 attains its receiving relation, the roll is released and the spring acts to advance the slide quickly into the magazine-openings 98. The slide, striking the bottom reinforcement P in the stack advances 15 this from the plate 46, so it falls through the opening in said plate and is deposited in the ring-opening 22 upon the plate 126. Any tendency of the reinforcement to be thrown beyond the opening 22 is prevented by its engagement with the 20 wall 122, which deflects it downwardly into the ring. If, during the ejection, the reinforcement resists movement, as because of projecting burrs, the spring-actuated slide will stop without injury to the parts. Upon restoration of the loader-arm 25 to its normal position, the cam-surface *b* withdraws the slide 96 from the magazine and retensions the spring 110. The ring 118 containing the reinforcement returns over the die 14, said reinforcement sliding first upon the plate 126 and 30 then upon the upper face of the die. With the loader-block back in its nail-receiving position at the foot-plate of the distributor, the openings *p* of the reinforcement are in registration with the die-block-passages. The operator, thereupon, 35 applies to the ring-opening 22 a heel or heel-portion H with its tread-end resting upon the reinforcement, lowers the jack 12 upon which a shoe has been placed until the heel-seat of said shoe is upon the heel and starts the power-operation 40 of the attaching machine. Clamping pressure is applied to the work, the drivers 16, upon which the previously delivered load of nails is resting, rise, and the points of the nails pass through the reinforcement-openings and into the 45 heel-portion to effect their simultaneous attachment to the shoe. These operations may continue until another size of reinforcement is required, when the turret is shifted, as already described, to bring the proper magazine into delivering position.

Having described my invention, what I claim as new and desire to secure by Letters Patent of the United States is:

1. The combination with a movable heel-holder, of means for supplying heel-reinforcements to the heel-holder, and mechanism arranged to drive nails through a reinforcement in the holder into a heel contained in the holder with said reinforcement.

2. The combination with heel-nailing mechanism, of means for transferring nails to said mechanism, a heel-holder movable under the control of the transferring means between the nailing mechanism and a position in which it may receive a heel-reinforcement, and means for supplying heel-reinforcements to the heel-holder.

3. In combination, nail-inserting means, mechanism for transferring nails to inserting means, mechanism for presenting a heel-reinforcement to the inserting means, mechanism for supplying reinforcements to the presenting mechanism, and means acting as an incident to the operation of one of the mechanisms for controlling the actuation of the other two mechanisms.

4. The combination with heel-nailing mechanism, of a magazine for heel-reinforcements, means for transferring nails to the nailing mechanism, a heel-holder movable under the control 5 of the transferring means between the nailing mechanism and the magazine, and means under the control of the transferring means for ejecting reinforcements from the magazine into the heel-holder.
- 10 5. The combination with heel-nailing mechanism, of a plurality of magazines for heel-reinforcements, any one of which magazines may be brought into delivering position, and means for ejecting the reinforcements one by one from the 15 selected magazine and positioning them for attachment to heels.
- 20 6. In a heel-attachment machine, heel-nailing mechanism, a heel-ring movable between the nailing mechanism and a position in which it may receive a heel-reinforcement, a magazine-tube 25 for heel-reinforcements, an ejector movable into the tube to deliver a reinforcement therefrom into the ring, and means made effective during the movement of the heel-ring for moving the elepector.
- 30 7. In a heel-attaching machine, heel-nailing mechanism, a heel-ring movable between the nailing mechanism and a position in which it may receive a heel-reinforcement, a magazine-tube 35 for heel-reinforcements, and ejector movable into the tube to deliver a reinforcement therefrom into the ring, and the movable member connected to both the ring and the ejector to control their movement.
- 35 8. In a heel-attaching mechanism, heel-nailing mechanism, a heel-ring movable between the nailing mechanism and a position in which it may receive a heel-reinforcement, a magazine-tube 40 for heel-reinforcements, an ejector movable into the tube to deliver a reinforcement therefrom into the ring, a spring by which the ejector is actuated to deliver a reinforcement from the tube to the ring, and means by which the ejector is retracted and the spring tensioned.
- 45 9. In a heel-attaching machine, heel-nailing mechanism, a heel-ring movable between the nailing mechanism and a position in which it may receive a heel-reinforcement, a magazine-tube 50 for heel-reinforcements, an ejector movable into the tube to deliver a reinforcement therefrom into the ring, loading mechanism movable to deliver nails to the nailing mechanism, and means connecting the loading mechanism to the heel-ring and to the ejector to control their movement.
- 55 10. In a heel-attaching machine, heel-nailing mechanism, a heel-ring movable between the nailing mechanism and a position in which it may receive a heel-reinforcement, a magazine-tube 60 for heel-reinforcements, an injector movable into the tube to deliver a reinforcement therefrom into the ring, a spring by which the injector is actuated to deliver a reinforcement from the tube to the ring, loading mechanism movable to deliver 65 nails to the nailing mechanism, and a cam movable by the loading mechanism to retract the ejector and tension the spring.
- 70 11. In a heel-attaching machine, heel-nailing mechanism, a heel-ring movable between the nailing mechanism and a position in which it may receive a heel-reinforcement, a magazine-tube 75 for heel-reinforcements, an injector movable into the tube to deliver a reinforcement therefrom into the ring, a spring by which the injector is actuated to deliver a reinforcement from the tube to
- the ring, loading mechanism movable to deliver nails to the nailing mechanism, a cam movable by the loading mechanism to retract the ejector and tension the spring, and a link joining the loading mechanism to the heel-ring.
12. In a machine for attaching heel-reinforcements, the combination with a nailing mechanism, of a holder for reinforcements of different sizes, said holder being movable between the nailing mechanism and a reinforcement-receiving position with one extremity of the reinforcements of all sizes at the same points in the respective positions, a magazine at the receiving position provided with adjustable means adapted to hold the extremities of the different reinforcements at a point corresponding to their positions in the holder, and means movable through an unvarying distance for ejecting the reinforcements from the magazine into the holder.
13. In a machine for attaching heel-reinforcements, the combination with nailing mechanism, of a holder for reinforcements of different sizes, said holder being movable between the nailing mechanism and a reinforcement-receiving position, and a magazine at the receiving position provided with a locating member rising through said magazine and adjustable to correspond to different sizes of reinforcements.
14. In a machine for attaching heel-reinforcements, the combination with nailing mechanism, of a holder for reinforcements of different sizes, said holder being movable between the nailing mechanism and a reinforcement-receiving position, and a magazine at the receiving position provided with a post rising through the magazine and with a side wall, both the post and side wall being variable in position in the magazine.
15. The combination with nailing mechanism, of a holder for a heel-reinforcement movable between the nailing mechanism and a reinforcement-receiving position, a rotatable turret, a plurality of magazines for reinforcements movable upon the turret, and locating means for the turret carried by each magazine and effective at the reinforcement-receiving position of the holder.
16. The combination with nailing mechanism, of a holder for a heel-reinforcement movable between the nailing mechanism and a reinforcement-receiving position, a rotatable turret, and a plurality of magazines for reinforcements movable upon the turret and each having a roll arranged to travel over a supporting surface, there being a depression in said surface to receive any one of the rolls at the reinforcement-receiving position of the holder.
17. The combination with nailing mechanism, of a holder for a heel-reinforcement movable between the nailing mechanism and a reinforcement-receiving position, a rotatable turret, a plurality of magazines for reinforcements movable upon the turret, locating means for the turret carried by each magazine and effective at the reinforcement-receiving position of the holder, and means movable by the operator to free the turret from the effect of the locating means.
18. The combination with nailing mechanism, of a holder for a heel-reinforcement movable between the nailing mechanism and a reinforcement-receiving position, a rotatable turret, a plurality of magazines for reinforcements movable upon the turret and each having a roll arranged to travel over a supporting surface, there being a depression in said surface to receive any one of the rolls at the reinforcement-receiving position

of the holder, and a member movable by the operator to elevate the magazine.

19. The combination with nailing mechanism, of a holder for a heel-reinforcement movable between the nailing mechanism and a reinforcement-receiving position, a magazine for reinforcements at the receiving position of the holder, a member movable in the magazine to eject the reinforcements successively therefrom, and deflecting means with which the ejected reinforcement may contact to direct it into the holder.

20. The combination with nailing mechanism, of a holder for a heel-reinforcement movable between the nailing mechanism and a reinforcement-receiving position, a magazine for reinforcements at the receiving position of the holder, a member movable in the magazine to eject the

reinforcements successively therefrom, deflecting means with which the ejected reinforcement may contact to direct it into the holder, and means to vary the position of the deflecting means with respect to the magazine.

21. The combination with nailing mechanism, of a holder for a heel-reinforcement movable between the nailing mechanism and a reinforcement-receiving position, a vertical magazine for reinforcements, a slide movable horizontally into the magazine to eject the bottom reinforcement therefrom into the holder, and a wall situated at the front of the magazine and against which the ejected reinforcement may strike in its descent into the holder.
